UNITED STATES PATENT OFFICE.

W. ALEX. WILLIAMSON, OF NEWARK, NEW JERSEY.

DESIGN FOR A PICTURE-HOOK.

SPECIFICATION forming part of Design No. 18,538, dated August 14, 1888.

Application filed July 14, 1888. Serial No. 280,010. Term of patent 7 years.

To all whom it may concern:

Be it known that I, W. ALEX. WILLIAMSON, a citizen of the United States, residing at Newark, in the county of Essex and State of New Jersey, have invented and produced a new and original Design for Picture-Hooks, of which the following is a specification, reference being had to the accompanying drawings, forming a part thereof.

In the accompanying drawings, Figure 1 is a front elevation of my design, and Fig. 2 is a side elevation of the same.

As indicated in the views to which reference is made above, my design for a picture-hook presents in front elevation two spreading wires, $a a'$, at the top of the hook, which spreading wires join and form a twist, b , which presents the same appearance on all sides. Below the

twist the wires are parallel and in front elevation form a small loop, c . Above the twist b 20 the spreading wires present the appearance of a hook, a' , when viewed in side elevation, and also the wires below the said twist in side elevation are formed into a hook, c' , which is much smaller than the upper hook. 25

I claim—

The design for a picture-hook herein shown and described, the same consisting of two spreading wires, $a a'$, twisted at b , and forming a loop at c in front elevation and hooks 30 $a' c'$ in side elevation.

W. ALEX. WILLIAMSON.
